UNITED STATES PATENT OFFICE.

FREDERICK HAITZ, OF TOWANDA, ILLINOIS.

UMBRELLA-SUPPORT.

SPECIFICATION forming part of Letters Patent No. 377,456, dated February 7, 1888.

Application filed June 6, 1887. Serial No. 240,451. (No model.)

To all whom it may concern:

Be it known that I, FREDERICK HAITZ, a citizen of the United States, residing at Towanda, in the county of McLean and State of Illinois, have invented a new and useful Improvement in Umbrella-Supports, of which the following is a specification.

My invention relates to an improvement in umbrella-supports; and it consists in the peculiar construction and combination of devices, that will be more fully set forth hereinafter, and particularly pointed out in the claims.

The object of my invention is to provide an umbrella-support that is adapted to attach an umbrella to a wagon or other vehicle or to an agricultural machine—such as a mowing-machine, a grain-binder, or corn-planter, &c.—said support being provided with means by which the umbrella may be adjusted vertically or horizontally or inclined to any desired angle.

In the drawings, Figure 1 is an elevation of an umbrella-support embodying my improvements. Fig. 2 is a vertical longitudinal sectional view of the same. Fig. 3 is a top plan view. Fig. 4 is a vertical sectional view taken on the line $x-x$ of Fig. 1. Fig. 5 is an enlarged detail view of T-shaped head.

A represents the socket, which is secured to the seat of the vehicle or machine by means of an arm, B. In the bottom of the vehicle is a socket, C, adapted to receive the lower end of a vertical standard, D, which standard passes through the socket A and is then bent outward at right angles, so as to clear the side of the vehicle and of the seat, and is then bent upward to a vertical position, as shown. The upper end of standard D is provided with a sleeve, E, which is rigidly connected thereto, and has a square vertical socket, F.

G represents a clamping-screw which extends through the threaded opening made in one side of the socket.

H represents a vertical rod which is made of metal and is adapted to slide vertically in the sleeve E. The upper end of the rod H is cylindrical in shape and is provided with a transverse threaded opening, I, and at a suitable distance from the upper end of rod H is a collar, K, which is provided with a series of vertical radial spurs, L.

M represents a T-shaped head which is provided with a depending sleeve or socket, N, and a transverse sleeve, O, at the upper end of the sleeve N. The latter is provided at its lower side with a series of inwardly-projecting teeth or offsets, P, which are adapted to pass through the spaces between the teeth L of the collar K. At a suitable distance from the upper end of the sleeve N is an inwardly-projecting annular offset, R.

S represents a coiled extensible spring which is arranged in the sleeve N. This spring encircles the upper cylindrical end of the rod H and bears on the upper side of the collar K, and thereby normally forces the rod H downward, so that the spur-teeth of the collar engage the vertical recesses in the sleeve N, and thus prevent the head from rotating on the rod.

U represents a screw or pin which extends transversely through the opening I in the upper end of rod H and bears normally against the offset R to limit the downward movement of the rod H.

V represents a set-screw which extends through one side of the sleeve N, and is adapted to engage the upper end of rod H and hold the latter while the screw or pin U is being inserted through the opening I.

W represents a horizontal bar, which is also made of metal, and extends through the longitudinal bore of the sleeve O, and the latter is provided with a set-screw, X, adapted to clamp the bar W at any desired longitudinal adjustment. One end of the bar W is cylindrical in shape and is adapted to enter a cylindrical sleeve, Y. At a suitable distance from the end of the bar W is an annular collar or flange, Z, the diameter of which is equal to the interior diameter of the sleeve Y.

A' represents a coiled extensible spring which is arranged around the cylindrical portion of the bar W, and bears between the front side of the flange Z and the outer end of the sleeve Y, the function of the said spring being to normally project the said sleeve outward to the end of the bar.

B' represents an arm which projects from the sleeve Y at right angles thereto, and C' represents a cylindrical stud, which also projects from the said sleeve and is arranged par-

allel with the arm B'. The latter has an outwardly-extending stud, D', at its extremity, which stud is adapted to engage either of a series of openings, E', with which a semicircular plate, F', that is attached to the outer end of the bar W, is provided.

By first moving the sleeve Y inward against the tension of the spring, so as to withdraw the stud B' from the opening E' with which it is engaged, the sleeve may be turned on the bar W to any desired angle. The stud C' is adapted to fit in a vertical socket at the lower end of the umbrella-handle, (not shown,) and a pin, G', extends transversely through the umbrella handle or thimble and through the stud C', so as to secure the umbrella firmly to the stud and prevent it from becoming accidentally disengaged therefrom. It will be readily understood that by turning the sleeve 20 on the supporting-bar W the umbrella may be inclined at any desired angle.

As the bar W is longitudinally adjustable in the head, the umbrella may be moved in or out, and by depressing the head, so as to cause the recesses or teeth in the lower end of the sleeve N to pass below the teeth in the collar on the rod H, the head may be turned on the said rod, so as to swing the bar W in a horizontal direction, and thus cause the umbrella 30 to be turned to any point of the compass.

I propose in practice to employ this umbrella-support in connection with the improved umbrella shown and described in my pending application for Letters Patent of the United States, Serial No. 235,237; but I do not wish to limit myself in this particular.

Having thus described my invention, I claim—

1. The combination, in an umbrella-support, 40 of the standard D, having the socket E and the set-screw G, the vertically-adjustable rod H, secured in the said socket and having the collar K, provided with teeth L, the head M, having the depending sleeve N, fitting on the

upper end of rod H and provided at its lower 45 end with the teeth or recesses to engage the teeth L, the springs bearing downward normally on the collar K, the horizontal bar W, secured in the upper side of the head A, and the sleeve on the bar W, adapted to turn 50 thereon and provided with the stud C' to enter a socket in the umbrella handle or thimble, and the arm or detent D', to engage a series of openings in a plate, F', on the end of the bar W, and thereby secure the sleeve thereon at 55 any desired inclination, substantially as described.

2. The combination, in an umbrella-support, of the vertical rod H, the head M at the upper end of the said rod, the horizontal bar W, secured in the said head and adjustable therein, the head being provided with the clamping-screw to secure the bar, and the sleeve secured to the bar W and adapted to turn thereon to any desired angle, the said sleeve having the 60 stud C' to enter the recess or socket in the umbrella handle or thimble, substantially as described.

3. In an umbrella-support, the combination of the standard H, having the collar K, provided with vertical teeth L, the head M, having the sleeve N to receive the upper end of rod H, the said sleeve being provided with the annular inwardly-projecting offset R, the spring S on the upper end of rod H and 70 bearing between the offset R and the collar K, for the purpose set forth, and the pin or screw extending transversely through the upper end of rod H above the offset R, substantially as described.

In testimony that I claim the foregoing as my own I have hereto affixed my signature in presence of two witnesses.

FREDERICK HAITZ.
